UNITED STATES PATENT OFFICE.

PETER MORAN, OF PHILADELPHIA, PENNSYLVANIA.

BURGLAR-ALARM.

SPECIFICATION forming part of Letters Patent No. 258,452, dated May 23, 1882.

Application filed March 22, 1882. (Model.)

To all whom it may concern:

Be it known that I, PETER MORAN, of Philadelphia, in the county of Philadelphia and State of Pennsylvania, have invented a new 5 and useful Improvement in Burglar-Alarms, of which the following is a full, clear, and exact description.

My invention relates to that class of burglar-alarms in which a gong is struck by clock 10 mechanism for giving the alarm; and to this end my invention consists in a novel construction and arrangement of parts, as hereinafter fully described, and pointed out in the claims.

Reference is to be had to the accompanying 15 drawings, forming part of this specification, in which similar letters of reference indicate corresponding parts in all the figures.

Figure 1 represents my new and improved burglar-alarm attached to the wall of a room 20 with several cords or wires leading therefrom to a door and windows. Fig. 2 is a front elevation of the alarm, the cover of the box in which the mechanism is contained being open; and Fig. 3 is a sectional elevation, taken on the 25 line *xx* of Fig. 2.

A represents the box in which the alarm mechanism is placed, which box is adapted to be secured to the wall or to any permanent object by means of the rings *a a*, or any other 30 suitable means for securing the box may be employed.

B is the clock mechanism, which is of ordinary construction, and does not require description in detail. *C* is the gong, and *D D* 35 represent the double-acting rods, of which there may be any desired number to suit the number of windows and doors with which it may be desired to connect the alarm. These rods *D D* are held in the box by means of the 40 posts *f f'*, through which the rods pass, which posts are secured in the box by means of the plates *i i'*, attached to or made integral with the posts, the said plates being perforated for the passage of screws or similar fastenings, 45 as shown in Figs. 1 and 2; and these rods *D D* are made double-acting by means of the springs *d*, placed upon the rods between the heads *e* of the rods and the post *f'*, and any 50 movement of the rods through the posts is communicated to the spring-held escapement-detent *E*, which is pivoted to the side of the box

by means of the pivoted plates *F*, pins or studs *b b* upon the plate *E*, and the pins or studs *h*, secured to or formed upon the said rods. The plates *F* are by preference made T-shaped, as 55 shown clearly in Fig. 2, with the divided end *j*, the parts of which straddle the pins *h*, and with the diagonal faces or edges *k k* at the inner end of the plates, which come between and against the pins or studs *b b*, as shown; and 60 there will be as many of these plates *F* as there are rods *D*.

To the outer ends of the rods *D* are secured the setting wires or cords *l*, which pass out the end of the box between the horizontal friction-rollers *c* and the vertical friction-rollers *c'*, and lead to the window or door with which it is desired to connect the alarm. The friction-rollers *c* and *c'* are held in the frame *L*, which is secured to the box in proper position, as shown 70 in the drawings, by means of screws or any other suitable fastenings.

In case there are several rods *D* in the alarm, the plates *F* will all be pivoted upon the same pivot, *j'*, suitable division-blocks being placed 75 between them, and the pins or stops *b b* in such case will be of sufficient length to reach past or above all of the plates *F*, so that the longitudinal movement in either direction of any one of the rods *D* will move the escapement-detent *E* and give the alarm.

Near the post *f*, through which the rods *D* pass, the rods *D* are perforated for the passage of the pin *g*, which is adapted to hold the rods against the action of the springs in such position that the escapement-detent will hold the alarm mechanism at rest.

In setting the alarm, the box having been first secured to the wall or some other stationary object, and the pin *g* being in place, the 90 cords *l*, any one or all of them, are first carried over suitably-arranged pulleys and drawn just taut and attached to the knob, catch, or any other part of the door or window. All of the cords (if more than one is to be used) having 95 been thus attached, the clock mechanism is to be wound up by the application of a key in the ordinary manner and the pin *g* removed, so that the rods *D* will be held against the action of the springs by means of the cords *l*. 100 In this position the alarm mechanism will still be at rest, and will remain so until one of the

windows or doors is opened or tampered with in such manner as to pull or loosen the cord or wire *l* attached to it. In case the cord be pulled, the spring *d* will permit the movement 5 of the rod *D*, which will move the plate *F*, which will move the escapement-detent and release the alarm mechanism; and should the cord or wire be cut or loosened or otherwise moved out of its set position the spring *d* will force 10 the rod downward or backward and will move the plate *F*, and in like manner also release the alarm mechanism and give the alarm. By this means it will be seen that any tampering whatever with the cord or wire will certainly 15 set the alarm mechanism in action.

By means of the friction-rollers *c* and *c'* it will be understood that the cords *l* may be carried in any direction from the alarm and still move easily over the rollers, thus increasing 20 the certainty of the action of the alarm.

Having thus described my invention, what I claim as new, and desire to secure by Letters Patent, is—

1. The combination, with escapement-detent and alarm mechanism, of the spring-pressed 25 sliding rods *D*, and the plate *F*, connecting the rods with the detent, substantially as and for the purpose set forth.

2. The combination, with the escapement-detent *E*, provided with the pins *b*, of the sliding rods *D*, provided with the pins *h*, and the T-shaped plate *F*, provided with the inclines *k* and the slot, substantially as and for the purpose set forth. 30

3. The combination, with the box *A*, provided with the perforated posts *ff'*, and the detent *E*, provided with pins *b*, of the rods *D*, the springs *d*, and the T-shaped plate *F*, provided with the inclines *k*, substantially as and for the purpose set forth. 35

PETER MORAN.
